ATTORNEY

UNITED STATES PATENT OFFICE.

MARY L. SMITH, OF MARLBORO, NEW HAMPSHIRE.

SHOE-FASTENER.

1,272,137.

Specification of Letters Patent.

Patented July 9, 1918.

Application filed October 18, 1917. Serial No. 197,307.

To all whom it may concern:

Be it known that I, MARY L. SMITH, a citizen of the United States, residing at Marlboro, in the county of Cheshire and State of New Hampshire, have invented certain new and useful Improvements in Shoe-Fasteners, of which the following is a specification.

This invention is an improvement in shoes and slippers and is directed more particularly to the method of fastening the same upon the feet of the wearer.

One object of the invention is to provide a means of securing a shoe or slipper upon the foot of a person so that the same will not slip up and down upon the heel and at the same time provide for thorough ventilation and free foot movement of the wearer.

20 A further object is to provide straps that lead from the counter and are detachably fastened at their free ends to the vamp, the straps being crossed, and at the point of intersection or crossing the straps being provided with friction material.

The invention broadly stated, comprises a shoe or slipper having a counter, a vamp connected to the counter by quarters, straps formed by slitting the quarters from adjacent the vamp backward to the counter, suitable fastening means for the free ends of the straps so that they may be secured adjacent the vamp, one of said straps being provided with an opening through which 35 the other strap may pass, thus providing for the crossing of the straps upon the instep of the wearer, one of the straps being provided with suitable friction material to prevent undue movement of the straps when in 40 use, said straps being formed integral with the quarters.

One practical form of construction and assembly will be described and illustrated in the accompanying drawings in which,

45 Figure 1 is a perspective view of a slipper formed in accordance with the preferred construction of the invention, and

50 Fig. 2 is a bottom plan view of one of the straps showing the friction material carried thereby, and

Fig. 3 is a sectional view to show the crossing of the straps.

In the preferred embodiment about to be described the slipper shown in Fig. 1 may 55 be provided with the usual sole 5 and the heel 6. Secured to the sole 5 is a vamp 7

which in the present illustration is continuous with the quarter 8 and the counter 9.

The straps 10 and 11 are preferably formed by slitting the quarters 8 from a point adjacent the vamp 7 backward to near the counter 9. The width of the straps 10 and 11 may be such as is desired and it will be seen that they are formed of the same material and are integral with the quarters 65 and counter. The slits which may be generally indicated at 12 and 13 showing the ends thereof are carried sufficiently backward to permit the straps 10 and 11 to cross over the instep of the user in a comfortable 70 manner.

The free ends of the straps 10 and 11 may carry parts of the snap fasteners 14 and 15. Such parts may be the socket portions of the snap fasteners while the ball portion 75 may be secured to and upon opposite sides of the vamp.

The straps 10 and 11 when in use preferably cross over so that the strap that originates upon the inside quarter will have its 80 free end fastened to the vamp adjacent the outside quarter.

In order to provide a means for holding the straps in their crossed position, the strap 11 is split. The strap 10 is then 85 passed through the slot or opening 11^a formed in the strap 11.

As shown in Fig. 1 by the dotted lines one of the straps is provided with the friction material 16. The friction material is 90 preferably placed upon the underside of the strap so that it will not rub the instep of the wearer as when walking the straps naturally move slightly. Similar friction material indicated at 17 may be inserted as 95 a lining upon the inside of the counter 9. This will serve to prevent the heel of the wearer from slipping up and down.

The slipper as shown is well adapted by means of the straps 10 and 11 and their 100 fastenings 14 and 15 to firmly maintain the shoe or slipper upon the foot of the wearer. By crossing the straps 10 and 11, the heel portion of the slipper is prevented from moving downward and away from the heel 105 of the wearer by means of the crossing straps which apply a restraining action. This restraining action occurs at the point of crossing of the straps upon the instep. This limits the amount of heel play. The 110 pull upon the snap fasteners 14 and 15 is more or less transversely of their axes and

thus they are ample to withstand the strain. Any other suitable type of fastening may be employed for the snap fasteners to provide a quick and ready means for detachably securing the free ends of the straps to the vamp portion of the shoe or slipper.

Minor changes in form, proportion and details of construction may be resorted to without departing from the spirit of the 10 invention or the scope of the appended claims:

1. The combination with a shoe having a heel and sole, of a counter and a vamp joined by quarters, a plurality of straps 15 formed by slitting the quarters from a point adjacent the counter forward to the vamp, means for detachably securing the free ends of the straps to the vamp, said straps being adapted to be crossed, and friction material 20 carried by one of the straps at the point of

crossing to prevent undue movement of the strap and to prevent wear of the hose of the wearer.

2. A shoe comprising a counter and a vamp joined by quarters, a plurality of straps formed from the quarters and adapted to extend from the counter to the vamp, means for detachably fastening the free ends of the straps to the vamp, one of said straps having an opening therein through which is adapted to pass the other strap for retaining the straps in a crossed position, and friction material attached to the underside of one of the straps.

In testimony whereof I affix my signature 35 in presence of two witnesses.

MARY L. SMITH.
